Patented Nov. 7, 1967

209,158

CORN SKEWER

Myron M. Levin, Lincolnwood, Ill.
(4315 N. Lincoln Ave., Chicago, Ill. 60618)

Filed Feb. 28, 1967, Ser. No. 5,997

Term of patent 14 years

(Cl. D44—4)

I claim:

The ornamental design for a corn skewer, as shown.
